UNITED STATES PATENT OFFICE

GRETCHEN B. SCHOENLEBER, OF MILWAUKEE, WISCONSIN, ASSIGNOR TO AMBROSIA CHOCOLATE COMPANY, OF MILWAUKEE, WISCONSIN, A CORPORATION OF WISCONSIN

DESIGN FOR A CANDY CONFECTION

Application filed May 25, 1932. Serial No. 43,903. Term of patent 7 years.

To all whom it may concern:

Be it known that I, GRETCHEN B. SCHOENLEBER, a citizen of the United States, residing at Milwaukee, in the county of Milwaukee and State of Wisconsin, have invented a new, original, and ornamental Design for a Candy Confection, of which the following is a specification, reference being had to the accompanying drawing, forming part thereof.

I claim:

The ornamental design for a candy confection, as shown.

GRETCHEN B. SCHOENLEBER.
